US00D999376S

(12) **United States Design Patent** (10) **Patent No.:** **US D999,376 S**
(45) **Date of Patent:** **** Sep. 19, 2023**

(54) **CO2 LASER APPLICATION SYSTEM**

(71) Applicant: **Alma Lasers Ltd.**, Caesarea (IL)

(72) Inventors: **Tomer Touviano**, Caesarea (IL); **Avner Lam**, Givat Haim M. (IL)

(73) Assignee: **Alma Lasers Ltd.**

(**) Term: **15 Years**

(21) Appl. No.: **29/795,166**

(22) Filed: **Jun. 17, 2021**

(51) LOC (14) Cl. **24-02**

(52) U.S. Cl.

USPC **D24/144**; D24/200

(57) **CLAIM**

The ornamental design for a CO2 laser application system, as shown and described.

DESCRIPTION

FIG. 1 is a perspective view showing the front, right side, and top of a CO2 laser application system;

FIG. 2 is a perspective view showing the bottom, right side, and rear thereof;

FIG. 3 is a front view thereof;

FIG. 4 is a rear view thereof;

FIG. 5 is a right side view thereof;

FIG. 6 is a left side view thereof;

FIG. 7 is an enlarged top view thereof; and,

FIG. 8 is an enlarged bottom view thereof.

The broken lines in the drawings depict portions of the CO2 laser application system and form no part of the claimed design.

1 Claim, 8 Drawing Sheets
